US0D1025803S

(12) **United States Design Patent** (10) **Patent No.:** **US D1,025,803 S**
(45) **Date of Patent:** **** May 7, 2024**

(54) **AUDIO/VIDEO DOORBELL AND DOOR VIEWER**

(71) Applicant: **Amazon Technologies, Inc.**, Seattle, WA (US)

(72) Inventors: **Mark Siminoff**, Mountain View, CA (US); **Matthew J. England**, Santa Monica, CA (US); **Christopher Loew**, Palo Alto, CA (US); **James Siminoff**, Pacific Palisades, CA (US)

(73) Assignee: **AMAZON TECHNOLOGIES, INC.**, Seattle, WA (US)

(**) Term: **15 Years**

(21) Appl. No.: **29/736,674**

(22) Filed: **Jun. 2, 2020**

Related U.S. Application Data

(62) Division of application No. 29/673,311, filed on Dec. 13, 2018, now Pat. No. Des. 889,300.

(57) **CLAIM**

The ornamental design for an audio/video doorbell and door viewer, as shown and described.

DESCRIPTION

FIG. 1 is a front, top perspective view of an audio/video doorbell and door viewer according to the present design; FIG. 2 is a back, bottom perspective view thereof; FIG. 3 is a front elevation view thereof; FIG. 4 is a back elevation view thereof; FIG. 5 is a left-side elevation view thereof; FIG. 6 is a right-side elevation view thereof; FIG. 7 is a top plan view thereof; FIG. 8 is a bottom plan view thereof; FIG. 9 is a front perspective view showing unclaimed environment of the audio/video doorbell and door viewer according to the present design; and, FIG. 10 is a back perspective view showing unclaimed environment of the audio/video doorbell and door viewer according to the present design.

The dashed lines depict portions of the audio/video doorbell and door viewer that form no part of the claimed design, and/or show environment of the audio/video doorbell and door viewer that forms no part of the claimed design.

1 Claim, 10 Drawing Sheets
